UNITED STATES PATENT OFFICE.

CHARLES R. KEERAN, OF BLOOMINGTON, ILLINOIS.

LEAD-PENCIL.

1,153,115.

Specification of Letters Patent. Patented Sept. 7, 1915.

Application filed October 6, 1913. Serial No. 793,588.

To all whom it may concern:

Be it known that I, CHARLES R. KEERAN, a citizen of the United States, residing at Bloomington, in the county of McLean and State of Illinois, have invented certain new and useful Improvements in Lead-Pencils, of which the following is a specification.

The present invention relates to that type of pencil in which the lead is fed out as desired from the body thereof by manually operated means.

The object of the present invention is to construct a device of the nature above described, which will permit of the use of a lead of small diameter, so that a sharpening of the lead is not necessary in order to maintain a point, the lead being so small that its normal size is the proper size for a writing point.

20 A further object of the invention is to provide a body for holding the lead, which is so constructed as to properly reinforce the lead and prevent its breaking during use.

25 A further object of the invention is to form said body of the same material from end to end, and of a one-piece construction, and to use a fibrous material possessing certain characteristics hereinafter set forth.

30 A further object of the invention is to so arrange the forward end of the bore that extends through the body as to have it perform the functions of a clutch to keep the lead from falling out from the body, and to so construct the device as to enable the bore 35 to be readjusted and continue its action as a clutch whenever it shall have become worn and enlarged to an extent to prevent its performing its clutching function on the lead.

40 A further object of the invention is to incase the body with a metallic or similar sheathing or casing, which will prevent outward expansion and splitting of the body, and which will give an attractive exterior to 45 the pencil; and to have the body serve as a filler for the outer sheathing to prevent the sheathing from becoming bent or mutilated.

50 The invention further consists in the features of construction and combination of parts hereinafter described and claimed.

55 In the drawings: Figure 1 is an elevation of a pencil constructed in accordance with the teachings of the present invention; Fig. 2, a longitudinal section of the device shown in Fig. 1; Fig. 3, a detail on an enlarged scale and in section, showing the forward

end of the body with the lead in position; and Fig. 4, a cross sectional detail on an enlarged scale, showing the contracted opening at the forward end of the body, which 60 serves as a clutch for the lead.

In the art to which the present invention relates, many forms of devices have been made, which provide means of one sort or another for feeding the lead out from a 65 barrel or body of the pencil, so as to eliminate the whittling away of the wood forming the body when it is desired to repoint or sharpen the pencil. In most of these devices, the lead is of a diameter so that it 70 must be cut away to form the writing point, and difficulty has been experienced in using a lead of small enough diameter so that the point is always present and eliminate the objectionable feature of having the lead break 75 during writing. This is owing to the fact that the lead is not properly reinforced by the body of the pencil, and hence when pressure is placed on the lead during the writing operation it will break. Further difficulty 80 has been experienced in preventing these small leads from dropping out from the body or barrel of the pencil, at undesirable times.

It is the primary object of the present invention to eliminate both of the above mentioned difficulties, although certain other novel characteristics, which will more fully appear hereinafter, are features of the present invention.

90 Referring, now, to the drawings, and particularly to Figs. 1 and 2, the device consists of a body or barrel 5, which is preferably made of some fibrous substance, of any suitable kind; the barrel is tapered at its forward end 6 to simulate in appearance an ordinary lead pencil, and is provided with an axially disposed longitudinal bore 7, the bore contracting at its outer end 8^a so as to gradually diminish in diameter toward the outer 100 end thereof. The portion 7 of the bore is intended to receive a lead 8, which lead is of small diameter or gage, so that by its nature it is always pointed without the necessity of cutting away a part of the lead to form the point, the diameter being small enough so that it constitutes a writing point without any additional sharpening. The lead is intended to have a sliding fit within the major portion of the bore 7, but the forward end 8^a of the bore, by reason of its contraction, affords a relatively tight fit for 105 110

the lead at this point, and hence there is friction created between the walls of the forward end of the bore and the lead, which friction serves to clutch or hold the lead and prevent its dropping out from the body or barrel at undesirable times.

The lead is fed forward out from the bore by any suitable means, the means illustrated consisting of a sleeve 9, having an interior 10 thread 10 meshing with a thread 11 on an outer shell or sheathing 12, and the sleeve 9 carries a wire or other member 13, which engages with the butt end of the lead, and, when the sleeve is turned, so as to advance 15 along the body of the pencil, the member 13 acts to shove the lead forward and out from the bore, as desired. No claim is made, however, to this particular means for feeding the lead, as it is understood that any suitable 20 means may be employed for performing this operation.

The sheathing 12 is preferably of metal or some analogous substance, and serves as a binder to prevent a splitting of the body, 25 and furthermore gives a finish to the pencil, since it may be formed of some of the finer metals, as, for instance, gold or silver, and thus make a very attractive device. The body 5 serves as a filler for this sheathing, 30 so that the finer metals can be employed as a sheathing without danger of their becoming dented or mutilated by use.

A further function of the sheathing is as follows: It will happen that by continued 35 usage the forward end 8^a of the bore 7 will become worn, and the tight fit and subsequent friction between the lead and the walls of the bore at this point will disappear. The body, as stated, is of fibrous material, 40 and when the bore becomes so worn it may be again made of the desired dimensions by simply dipping the end of the pencil in water, the water will swell the fibrous composition of the body, and since it cannot expand outwardly because of the sheathing 12, it will expand inwardly and reduce the diameter of the bore, thus readjusting the clutch to operating position.

It will be noted that a portion 14 of the 50 body extends beyond the end of the sheathing. By this construction a further means

is afforded for reestablishing the close fit between the lead and the forward end 8^a of the bore. This means consists in lightly tapping the projected end of the body, which 55 will result in a compression of the same and a closing and consequent reduction in diameter of the bore.

It will further be noted that the point of gripping of the lead is right at the point 60 of projection of the lead from the body, so that a reinforcement is given to the lead close to the writing point, thus preventing breaking, since so little of the lead need be projected as to render it difficult to break 65 the small projecting portion. If the grip on the lead were further back in the bore, then there would be sufficient leverage between the writing point and the point of grippage to cause a fracture of the same. 70

It will be further noted that the body 5 is of a relatively large transverse thickness throughout its length, thus giving a firm and rigid reinforcement for the lead throughout the body of the pencil. The forward end 14 75 of the body, as will be seen, is of a relatively blunt construction and is not of a nature which will break under pressure or readily become mutilated.

The pencil is extremely cheap and simple 80 to manufacture and will prove durable in use and extremely simple of operation.

I claim:

A pencil comprising a body portion of fibrous material, said body having a bore 85 therethrough, said bore being contracted at the outer end thereof to a size to give a tight fit of the lead therein and being of a size throughout the remainder to permit of a sliding fit of the lead therein, said contracted portion serving as a clutch to maintain the lead in position, a metallic casing surrounding the body portion and terminating short of the end of the body portion, and means for forcing the lead outward 95 through the bore in said body portion, substantially as described.

CHARLES R. KEERAN.
